(57) **CLAIM**

The ornamental design for a cyclorama light, as shown and described.

DESCRIPTION

FIG. 1 is a perspective view of a cyclorama light embodying the present invention.

FIG. 2 is a front view of the cyclorama light of FIG. 1.

FIG. 3 is a rear view of the cyclorama light of FIG. 1.

FIG. 4 is a right side view of a cyclorama light of FIG. 1.

FIG. 5 is a left side view of the cyclorama light of FIG. 1; and,

FIG. 6 is a top view of the cyclorama light of FIG. 1.

The elements shown in broken lines are included for the purpose of illustrating environment and form no part of the claimed design.

The bottom view of the design is not a matter of ornamental concern because the bottom view is obstructed by the surface upon which the light is positioned. Accordingly, this view has been omitted.
